UNITED STATES PATENT OFFICE.

THOMAS ATCHASON, OF NEWARK, NEW JERSEY.

TRACE-FASTENER.

SPECIFICATION forming part of Letters Patent No. 678,711, dated July 16, 1901.

Application filed December 3, 1900. Serial No. 38,402. (No model.)

To all whom it may concern:

Be it known that I, THOMAS ATCHASON, a citizen of the United States, residing at Newark, county of Essex, and State of New Jersey, have 5 invented certain new and useful Improvements in Trace-Fasteners, of which the following is a specification.

My invention relates to trace-fasteners; and the object of it is to provide a device 10 which shall be simple in construction, durable in use, and comparatively inexpensive of production and by means of which all liability of the trace becoming accidentally disengaged is entirely obviated. With this object in view I provide a trace-fastener constructed substantially as hereinafter more fully described and claimed, and illustrated in the accompanying drawings, wherein—

Figure 1 is a plan view of one end of a 20 whiffletree with my improved trace-fastener in position and closed on the trace, showing in dotted lines the trace-fastener disengaged from the trace. Fig. 2 is a side view of the same, partly in section.

25 My improved trace-fastener consists of two members, lettered, respectively, *b* and *c*.

c designates an eccentric lever made from a single piece of wire of approximately triangular shape. The sides of the eccentric lever 30 are bent upward and provided near its base with an eye *g*. The ends of the lever *c* are bent inwardly and engage with a bush *a*. The bush *a* is driven in the whiffletree *e* near its outer extremity and forms the fulcrum for 35 my improved trace-fastener.

b is a yoke also made from a single piece of wire and of an irregular oblong shape, embracing the outer extremity of the tree, the sides of said yoke being turned outward, so 40 as to form a rectangular recess for the reception of the end of the trace *f*. The ends of the yoke *b* are bent inwardly and pass through the eyes *g* of the lever *c*.

d represents a piece of felt, rubber tubing, 45 or other suitable yielding material secured to the yoke *b* at its outer extremity and engaging with a notch or groove in the end of the whiffletree to receive the pressure imparted to it by the eccentric lever *c* and also 50 to prevent it from slipping.

The mode of operation is as follows: The cockeye of the trace is slipped over the end

of the whiffletree while the trace-fastener is in the position indicated by dotted lines in Fig. 1. The lever *c*, which carries the yoke 55 *b*, is then pressed toward and against the rear side of the whiffletree, thus causing the yoke *b* to pass over and firmly clamp the end of the trace, as illustrated.

I do not confine myself to the particular 60 materials described in the specification, as other well-known materials may be employed without departing from the spirit of my invention.

Having now described my invention, what 65 I claim as new, and desire to secure by Letters Patent, is—

1. A trace-fastener comprising a lever of wire having eyes in the sides thereof near to its base and with ends bent inwardly adapted 70 to pivot in a bush extending through the whiffletree and adapted to fulcrum thereon, and a yoke made of wire having inwardly-bent ends adapted to pass through the eyes in said lever, and rectangular bent sides to 75 admit of the trace passing through them; the said lever by its eccentric action being adapted to draw the said yoke against the end of the whiffletree, substantially as described.

2. In a trace-fastener the combination with 80 a lever of wire having eyes in the sides thereof near its base and bent ends forming a fulcrum pivoted to a bush extending through the whiffletree, of a yoke of wire having inwardly-bent ends and rectangularly-bent 85 sides adapted to hold the trace in place and to clasp the said yoke to the whiffletree by the eccentric action of said lever, substantially as described.

3. In a trace-fastener the lever *c* having 90 eyes *g*, and ends bent inwardly pivoted in the bush *a* extending through the whiffletree, the yoke *b* connected with lever *c* at the eyes *g* and cushion *d* adapted to coöperate to clasp the trace *f* and hold it securely in place upon 95 the whiffletree, substantially as described.

In testimony whereof I, THOMAS ATCHASON, have signed my name to this specification, in the presence of two subscribing witnesses, this 30th day of November, 1900.

THOMAS ATCHASON.
